O. S. FIELD

LIGHT SOCKET

Filed April 6, 1921

Inventor:
Oscar S. Field,
by A. R. Vercill,
His Attorney.

UNITED STATES PATENT OFFICE.

OSCAR S. FIELD, OF ROSELLE, NEW JERSEY, ASSIGNOR, BY MESNE ASSIGNMENTS, TO UNION SWITCH & SIGNAL CO., OF SWISSVALE, PENNSYLVANIA, A CORPORATION OF PENNSYLVANIA.

LIGHT SOCKET.

Application filed April 6, 1921. Serial No. 459,199.

This application relates to certain improvements in sockets for electric lamp bulbs and particularly that kind known as the bayonet cap type.

5 The particular object of the invention is to provide a socket which will correctly align the bulb and eliminate rocking on the pins of the lamp case, which is a defect common to sockets which are now commercial.

10 A further object of the invention is to provide means whereby the filament of the bulb is accurately aligned in a definite position, such as in the focal point of a reflector or lens.

15 Another object is to provide a socket which may be adjusted, in order to focus the same, together with means whereby any subsequent bulb placed in the socket will automatically assume a correct location.

20 Further objects of the invention will be apparent from the accompanying description and appended claims.

Fig. 1 shows a side elevation of the socket with a bulb inserted therein.

25 Fig. 2 is a rear elevation of the same.

Fig. 3 is a section through the socket with the bulb removed.

Fig. 4 is a plan view of the socket and bulb.

30 It will be apparent that while these figures disclose one particular form of construction of the apparatus the construction may be modified without departing from the spirit of the invention.

35 In order to be sure of the correct alignment of the filament and the interchangeability of the bulbs, all bulbs to be used with the socket are first of all correctly mounted in their base in such a manner that the filament 1 is accurately located in relation to

40 the bayonet cap pins 2. This may be done in various manners and does not constitute a part of this invention. Pins 2 are accurately located in the base 3 and are displaced

45 from one another by an angle of 180° thereby placing the pins an equal distance from the upper and lower sides of the base 3 when viewed from the plane shown in Fig. 1 so that the pins 2 will always assume a position

50 on a horizontal axis of the base irrespective of which way the bulb is inserted in the socket.

The socket comprises a metal shell 4 which

has a forward extension 5 which is cut away at 6, leaving the shell at this part open. It 55 is further provided with oblique slots 7 and 8 adapted to take the bayonet cap pins 2. This shell is furnished with an insulating member 9 which is adapted to carry spring pressed contact studs 10 and 11 of a type 60 well-known in the art. By referring to Fig. 3 it will be seen that the contact stud 10 is located slightly in advance of the contact stud 11, the purpose of which will be explained hereafter.

65 The shell 4 is further provided with a keyway 12 and is tapped at 13 in order to take the adjusting screw 14. The side of the shell is cut away at 15 to provide an outlet for the leads 16 and 17 which are connected to the contact studs 10 and 11 respectively. This shell 4 is adapted to slide in a tube 18 of insulating material which is carried in the supporting member 19 which may be a part of the body of the lamp or other 70 device in which the light is used. A key 20 of insulating material is provided which is adapted to fit into a recess formed in the supporting member 19, the object of this key being to prevent rotating of the shell 4. The 75 screw 14 is adapted to pass through insulating bushing 21 and a spring 22 is provided which presses against the end of shell 4 and is insulated from the supporting member 19 by means of a washer 23 of insulating material.

80 It will be apparent from this construction that upon rotation of the screw 14, the shell 4 will be moved forward or backward in accordance with the direction of rotation, 90 thereby comprising means for a horizontal adjustment of the shell which forms the light carrying member.

85 The operation of the device is as follows:—

95 In order to insert a bulb the pins 2 of the bulb are laid upon the flat surfaces 24 of the cut away section 6. The bulb is then forced backward against the pressure of contact studs 10 and 11 until the pins pass 100 off the surfaces 24 when they are forced down in the oblique slots 7 and 8. Upon release of pressure from the bulb it is apparent that the contact springs 10 and 11 will force the bulb forward, forcing the pins 105 2 into intimate contact with the oblique sur-

faces 25 and 26 of the slots 7 and 8. Owing to the horizontal pressure exerted upon the bulb and the angle of the slots at the surfaces 25 and 26, the pins 2 will be caused to travel down the oblique surface until the base 3 is brought into intimate contact with the inner surface 27 of the shell 4. On account of the upper stud 10 being arranged slightly in advance of the lower contact stud 11 it will be apparent that there is a tendency for the bulb to be tilted in a downward direction, thereby insuring base 3 remaining in intimate contact with the inner surface 27 throughout its whole length.

From the above description it will be seen that when a bulb is inserted in the socket it will automatically assume a definite position determined by the inner surface 27 of the shell 4, and the bayonet cap pins 2 in the slots 6 and 7.

It will further be seen that all tendency for the bulb to rock about the pins 2 has been eliminated, due to the fact that the base 3 has been brought into this intimate contact with surface 27; and because the filament 1 is in accurate location in relation to the pins 2 on the base 3, the filament will assume a definite pre-determined position in relation to the socket. It will further be seen that in view of all bulbs being based with the filament accurately located in relation to the pins, that any bulb may be inserted in the socket with the assurance that the filament will accurately assume its correct position.

It is further apparent that with the construction disclosed the shell 4 which comprises the lamp socket is completely insulated from the supporting member 19 and that after the socket has been adjusted the recess 28 may be filled with any desirable sealing compound, thereby preventing the socket being changed in its adjustment.

What I claim is:

1. In a light socket for co-operation with an electric bulb having a bayonet base, a socket member open at one side and having oblique slots formed therein to receive the pins of the lamp base, and a spring pressed contact stud insulatively mounted therein, whereby upon pressure being exerted by the contact stud the base of the bulb is forced forwardly and transversely into intimate contact with the wall of the socket member to align the bulb in two planes.

2. In a light socket for co-operation with an electric bulb having a bayonet base, a socket member open at one side and having oblique slots formed therein to receive the pins of the lamp base, and spring pressed contact studs insulatively mounted therein, one being slightly in advance of the other, whereby upon pressure being exerted by the contact studs the base of the bulb is forced forwardly and transversely into intimate contact with the wall of the socket member to align the bulb in two planes.

In testimony whereof, I have signed my name to this specification.

OSCAR S. FIELD.
